United States Patent

Des. 241,823
Patented Oct. 12, 1976

241,823

CIRCUIT ANALYZER OR SIMILAR ARTICLE

Marnie Carlton Averitt, Timonium, Md., assignor to
AMP Incorporated, Harrisburg, Pa.

Filed Sept. 18, 1974, Ser. No. 507,654

Term of patent 14 years

Int. Cl. D10—04

U.S. Cl. D10—46

FIG. 1

FIG. 2

FIG. 3

FIG. 1 is a top plan view of a circuit analyzer or similar article showing my new design;

FIG. 2 is a front elevational view thereof, the rear being a mirror image thereto;

FIG. 3 is a left side elevational view thereof, the right side being a mirror image thereto.

The broken line disclosure of electrical terminals is for illustrative purposes only.

I claim:

The ornamental design for a circuit analyzer or similar article, as shown and described.
